UNITED STATES PATENT OFFICE.

FRANK WATT, OF MARQUETTE, MICHIGAN.

DESIGN FOR A CHAIR-LEG TIP.

SPECIFICATION forming part of Design No. 30,425, dated March 28, 1899.

Application filed March 1, 1899. Serial No. 707,408. Term of patent 7 years.

To all whom it may concern:

Be it known that I, FRANK WATT, a citizen of the United States, residing at Marquette, in the county of Marquette and State of Michigan, have invented and produced a certain new and original Design for Chair-Leg Tips; and I do declare the following to be a full, clear, and exact description of the invention, such as will enable others skilled in the art to 5 which it appertains to make and use the same.

My invention has relation to a new and original design for chair-leg tips.

The leading feature of my design consists in a cylindrical body portion and a circular base portion, the upper and lower faces of 15 which are concave and the sides of which are rounded.

In the drawings, Figure 1 is a perspective view of my chair-tip. Fig. 2 is a vertical sectional view, and Fig. 3 is a bottom plan view. 20

In the drawings, 1 denotes the cylindrical body portion, and 2 the circular base portion, having concave upper and lower faces 3 and 4, respectively, and rounded marginal edges 5.

What I claim is—

The design for a chair-leg tip, as herein shown and described.

In testimony whereof I have hereunto set my hand in presence of two subscribing witnesses.

FRANK WATT.
